UNITED STATES PATENT OFFICE.

MITCHEL V. MOISAN AND ANNA R. HEYWOOD, OF CENTRAL SQUARE, NEW YORK.

EDUCATIONAL GAME.

Application filed July 16, 1925. Serial No. 44,012.

To all whom it may concern:

Be it known that we, MITCHEL V. MOISAN and ANNA R. HEYWOOD, citizens of the United States, residing at Central Square, 5 county of Oswego, and State of New York, have invented certain new and useful Improvements in an Educational Game, of which the following is a specification.

The present invention relates to games, 10 and more particularly to games of the educational type.

An object of this invention is to provide a game apparatus which will not only afford amusement to children, but will also 15 teach them the alphabet and also to distinguish colors one from another.

Another object of this invention is to provide an educational game board and game pieces for use on the board which are of 20 simple construction and which form the basis of a simple method of operation or use in playing the game so that the underlying principle of the game may be easily grasped even by very young children.

The invention further aims at the provision of a game board having spaces thereon which are colored to distinguish the spaces from one another and to provide game pieces which are similarly colored and which bear 25 the letters of the alphabet and which are arranged with their colors and the letters of the alphabet in sequence corresponding to the arrangement of the colors in the spaces of the board so that when the game pieces are applied to the spaces on the board in 30 proper order to match the colors, the letters of the alphabet will appear in proper sequence, and so that when the game pieces are applied to the spaces on the board in the proper sequence of the letters of the alphabet the colors of the game pieces will correspond or match the colors of the spaces upon which they are placed. The bright 35 colors attract and hold the interest of the children, and the children soon memorize the letters and not only learn to distinguish the letters, but to also distinguish the colors.

The above and various other objects and 40 advantages of this invention will in part be described in, and in part understood from the following detailed description of the present preferred embodiment, the same being illustrated in the accompanying drawing, wherein:

Fig. 1 is a plan view of a game board constructed according to the present invention.

Fig. 2 is a plan view of a group of game pieces to be played on one end of the board.

Fig. 3 is a similar view of a second group of game pieces to be played on the other end 60 of the board, and

Fig. 4 is a plan view of the group of starter pieces employed.

Referring to the drawing 10 designates a game board of any suitable material to withstand wear and which may be given any desired configuration, such as rectangular as shown in Fig. 1.

The upper face of the board is provided at each end portion with a group of spaces 70 11 which are of suitable size and are arranged in rows or the like to correspond to the number of letters in the alphabet. In the present instance each group is composed of three rows of nine spaces each and with the last space 12 left blank while the other spaces are colored so as to contradict distinguish the same from one another, and the colors may be arranged in any suitable order or sequence to more clearly distinguish the spaces 80 11 from each other and to better impress upon the mind of a child the differences between the different colors. Each group of spaces 11 is preferably correspondingly formed and colored so that the ends of the 85 game board 10 are alike.

Two sets or groups of game pieces 13 and 14 are provided. Each group has twenty-six game pieces corresponding to the number of letters in the alphabet, and the game 90 pieces 13 are distinguished from the game pieces 14 in some suitable manner, such as by exterior configuration. The game pieces 13, as shown in Fig. 2, may be in the form of squares or right angled blocks, while the 95 game pieces 14, as shown in Fig. 3, may be round or of disk form. These distinguishing characteristics as to form readily segregate the groups by the touch as they are identified by the manner in which they are 100 grasped and moved.

Each group, 13 and 14, of game pieces is provided not only with the letters of the alphabet imprinted or otherwise suitably delineated upon the upper faces of the game 105 pieces, but these characters are given different colors which correspond to the colors of the groups of spaces 11 on the game board. The letters of the alphabet are consecutively colored in a sequence corresponding to that 110 of the coloring of the spaces 11 in each group so that the first character "A" is colored ac-

cording to the first space 11 in each group, the second character "B" is colored to correspond with the coloring in the second space of each group of spaces 11 of the game board, and the coloring of the characters 13 and 14 and the spaces 11 are similar throughout the entire twenty-six characters and spaces.

The game device is provided with a number of starter pieces 15, shown in Fig. 4 and which comprise flat pieces of any suitable configuration such as rectangular as shown, and which each have upon one face a number adapted to be turned down upon the central portion of the board 10 so as not to be seen by the players. The starter pieces 15 are provided with the numbers 1, 2 and 3 for a purpose which will subsequently appear.

In playing the game, each player takes a group of the game pieces 13 and 14, and arranges them with their characters facing upwardly into a position near the adjacent end of the board 10, and may arrange the pieces in rows or otherwise. It of course is not essential to arrange the game pieces in any particular manner or sequence. The three starter pieces 15 are now placed face downward upon the middle portion of the board 10 and the palm of the hand is spread over them and moved about in suitable fashion to change the relative positions of the starter pieces 15 so that they cannot be identified by the players according to the numbers which they bear.

The players now each select one of the starter pieces 15 and turn the same upward to find the numbers which they have drawn. If one player turns up the number two, that player is entitled to place the first two game pieces, 13 or 14 upon the respective first two spaces 11 of his group. If the other player turns up the number three, that player is entitled to place the first three game pieces, 13 or 14, upon the corresponding first three spaces 11 of his group. Of course, if a player turns up the number one he is entitled only to place but one game piece, 13 or 14, upon the corresponding first space 11 of his group.

After the game pieces 13 and 14 have been placed by the players upon their respective spaces 11, and in accordance with the numbers turned up, the player who had turned up the highest number, such as "3", now cries "Race", or some such similar expression indicating that the contest or race is to start. The players now proceed as rapidly as possible, and without any order in playing, proceed to place the game pieces 13 and 14 in proper sequence and with matched colors in the corresponding spaces 11. The player who is the first to place all of his game pieces correctly in his group of spaces 11 is adjudged the winner of the game. Of course,

various rules of the game may be devised and the winner of the game may be the one having the highest number of points after four races have been played, and each race may count twenty-five points.

The element of chance embodied in the game is the selection of a starter piece 15 which affords a more or less handicap to one of the players, and the winning of the game depends upon the ability and celerity of the players in selecting and matching up the colors of the respective game pieces 13 and 14 with the blank or colored spaces 11 as they are played upon in sequence from row to row.

It is of course understood that various changes and modifications may be made in the detail of construction and design of the above specifically described game apparatus without departing from the spirit of the invention, and limited only by the scope of the following claims.

What is claimed is:

1. An educational game comprising a board having separate groups of spaces thereon with the spaces of each group contradistinguished by different colors, a plurality of game pieces having configurations thereon, said game pieces being colored in sequence according to the sequence of the colors on the spaces on said board, and a plurality of starter pieces having configurations upon one side adapted to be turned down and shuffled on the face of the board to determine the placing of different numbers of the groups of game pieces upon their respective spaces.

2. An educational game comprising a board having separate groups of spaces thereon with the spaces of each group contradistinguished by different colors, a plurality of game pieces corresponding to the groups of spaces on the board and having configurations thereon on one side, said game pieces also being colored in sequence according to the sequence of the colors on the spaces on said board, and a plurality of starter pieces for determining the various game pieces to be placed upon their respective spaces on the board.

3. An educational game comprising a board having separate groups of spaces thereon correspondingly arranged in rows and contradistinguishing colors, separate groups of game pieces bearing the letters of the alphabet thereon in contradistinguishing colors arranged in sequence corresponding to the sequence of colors of the spaces in said groups of spaces on the board, and a plurality of starter pieces having different numbers upon one side adapted to be turned down and shuffled on the face of said board to determine by chance the placing of different numbers of the groups of game pieces upon their respective spaces.

4. An educational game comprising a board having rows of spaces grouped together toward the opposite ends of the board, said spaces being correspondingly colored in the separate groups to contradistinguish the spaces one from another, independent sets of game pieces of different configurations adapted to be placed upon the spaces on the board, said game pieces bearing letters of the alphabet in colors corresponding to the colors of the spaces on the board and the coloring of the letters being in proper sequence throughout the alphabet and in accordance with the consecutive coloring of the spaces on the board for determining the correct positioning of the game pieces on the spaces on the board in accordance with the sequence of the letters in the alphabet, and a plurality of starter pieces bearing numbers on one side and adapted to be inverted and shuffled on the game board for selection by chance by the players to determine the initial positioning of the game pieces on the board.
